IMPROVEMENT IN GATES.

RILEY JAMES GILBERT, OF HANOVER, WISCONSIN.

Letters Patent No. 60,171, dated December 4, 1866.

SPECIFICATION.

TO ALL WHOM IT MAY CONCERN:

Be it known that I, RILEY JAMES GILBERT, of Hanover, Rock county, State of Wisconsin, have invented a new and improved Gate; and I do hereby declare that the following is a full and exact description thereof, reference being had to the accompanying drawings, in which—

Figure 1 is a view in perspective of my gate.

Figure 2 is an end view, showing how the inclined carrying-beams are operated.

Figure 3 is a front or side view, with parts removed to show how the inclined carrying-beams are connected and supported.

Figure 4 is a cross-section of carrying beam B, at the point of support to the heel post a, showing how the latter is connected to and supported by the former.

Figure 5 is a cross-section of carrying-beam C, at the point of support to the head post b, showing how the latter is connected to and supported by the former; and

Figure 6 is similar to fig. 4, with the addition to the beam of a side cap or weather strip, r.

The nature of my invention relates to that class of fence or farm gates called gravitating gates, and consists in supporting a gate on wheels on two carrying-beams; so connected to each other and to a central post that, raising or depressing the end of one, both beams are inclined in either direction, thereby causing the gate to gravitate to an open or closed position at pleasure, and in deflecting or turning up the outer end of one or both carrying beams, so as to aid in the starting and stopping of the gate.

To enable others skilled in the art to make and use my invention, I will proceed to describe its construction and operation.

I construct the gate, A, of any desired form, providing it with heel and head posts, a and b, to which are attached by straps, c, or otherwise, the wheels or pulleys, d, that run on the rails, e e, of the carrying-beams, B and C. These beams are connected by the bar D, and are attached to the post E, at i and S, figs. 1 and 3, in such a manner as to allow their outer ends to move freely up and down. To protect the wheels, d, and rails, e, from the rain and snow, I cover the beams with a cap, g, that may also extend down in the form of a side cap, r, for the same purpose. The outer ends of the carrying-beams are guarded and kept in position by being made to play in mortises in or through the posts, F and R. To steady the gate, I employ the side rolls, u and v. To support and strengthen the posts, E and F, I usually join their tops by a cap, H. The post F has also a cross-beam, I, from which depend the swinging fulcrum, M M, of the levers, L L, that are attached to the outer end of the carrying-beam, B, and have depending handles, N N, with which the gate may be opened or closed.

To operate this gate it is only necessary to pull down or push up either of the handles N N, thereby raising or depressing the outer ends of the carrying beams and causing them to present an incline either to the right or left-hand direction, down which runs the gate to an open or closed position. To aid in starting the gate, by causing the carrying-wheels to rest on a steeper incline, I deflect or turn up the outer ends of the carrying-beams, as shown by C, figs. 1 and 3. This construction also tends to retard the velocity of the gate, or stop it, during the last part of its movement. It will be seen that this gate may be used as a double gate, that is, two gates opening in opposite directions may be used together. In that case everything is doubled except the post F (which is dispensed with) and the handles, levers, and fulcrum, N, L, and M; and the outer ends of the carrying-beams, B, of the two gates are joined, so as to allow both gates to be operated by the same levers, L.

What I claim as new, and for which I desire Letters Patent, is—

1. The carrying-beams B and C, when constructed, arranged, and used with or without the side cap, r, substantially as and for the purpose set forth.
2. The combination and arrangement of the handles N, levers L, swinging fulcrum M, carrying-beams B and C, connecting bar D, gate A, posts F E R, and cross-beam I, substantially as and for the purpose set forth.

RILEY JAMES GILBERT.
